UNITED STATES PATENT OFFICE.

HENRY REINACH, OF CHICAGO, ILLINOIS, ASSIGNOR OF ONE-HALF TO
CHARLES REINACH, OF SAME PLACE.

CHECK-VALVE.

SPECIFICATION forming part of Letters Patent No. 588,779, dated August 24, 1897.

Application filed December 26, 1896. Serial No. 616,998. (No model.)

To all whom it may concern:

Be it known that I, HENRY REINACH, a citizen of the United States, residing at Chicago, in the county of Cook and State of Illinois, 5 have invented certain new and useful Improvements in Check-Valves, of which the following is a specification.

The object of my invention is to provide a simple, economical, and efficient check-valve; 10 and the invention consists in the features, combinations, and details of construction hereinafter described and claimed.

In the accompanying drawings, Figure 1 is an elevation of my improvement as attached 15 in position ready for use; Fig. 2, a vertical longitudinal sectional elevation of my improved check-valve; and Fig. 3, a transverse sectional view, taken on line 3 of Fig. 2, looking in the direction of the arrow.

20 In the art to which this invention relates it is well known that if a chip or piece of dirt gets caught between the valve and seat it keeps the valve open and allows the water or fluid to seep through, thus destroying the efficiency of the valve. Again, in valves of 25 this particular class if it be desired to let the water out that is above or to the rear of the check the pipes have to be taken apart and the valve removed, so that it causes considerable annoyance and delay to let the water or 30 fluid out. My invention is intended to remove these objections and provide a valve in which the danger of chips or dirt interfering with the proper working thereof is minimized 35 and which is further provided with mechanism by which the fluid above the check may be allowed to pass through without disturbing the valve proper.

In constructing my improvement I prefer- 40 ably make a valve-casing in two parts A and A'. The part A is provided with a tubular raised seat portion a , having a sharp upper portion a' , on which the valve proper may rest. This seat portion is so constructed and ar- 45 ranged that it provides an annular chamber a^2 between it and the casing.

I provide a valve proper, B, having depend- 50 ing wings b , that are inserted in the tubular portion of the valve-seat and act as a guide, while the upper portion of the valve is pro- 55 vided with a rod B' , that is passed through a perforation in a guide-bar b' . I provide this valve with a cushion portion b^3 , that im- 60 pinges against the seat, so that when fluid-

pressure is exerted against the valve the seat 55 is forced slightly into the cushion portion and effectually prevents the passage of liquid or fluid therethrough. From the foregoing it will be seen that if any chips or dirt pass up through the tubular part A^3 of the valve- 60 casing it will be washed over the sharp edge and not retained on the seat portion to interfere with the proper working of the valve.

In order to allow the liquid or fluid that is confined above or to the rear of the valve 65 proper to escape, I provide the tubular portion a with a perforation or supplementary valve-seat C and screw-thread a valve C' in the valve-casing, so that by turning this screw in or out the perforation or valve-seat is 70 opened or closed and permits the liquid to escape without necessitating the disconnecting of the pipes or taking down the valve.

While I have described my invention with more or less minuteness as regards details 75 and as being embodied in certain precise forms, I do not desire to be limited thereto unduly any more than is pointed out in the claim. On the contrary, I contemplate all proper changes in form, construction, and 80 arrangement, the omission of immaterial elements, and the substitution of equivalents as circumstances may suggest or necessity render expedient.

I claim—

In a check-valve, the combination of two 85 tubular portions forming the valve-casing and secured together so as to be separated longitudinally, the lower portion being provided with a centrally-raised tubular portion 90 forming a valve-seat and an annular channel between it and the exterior casing, a cushion-valve having depending arms longitudinally movably seated on the valve-seat and provided with an upwardly-projecting rod, a 95 guide-bar in the upper valve-casing to assist in positioning the valve and guide it in its movements, an auxiliary-valve perforation in the upwardly-projecting valve-seat located above the bottom of the annular chamber, and a screw-threaded valve extending through 100 the valve-casing to open or close this auxiliary-valve perforation, substantially as described.

HENRY REINACH.
